METHOD AND APPARATUS FOR OPENING,
CARDING, AND CLEANING FIBROUS MA-
TERIALRussell Lee Brown, Lowell, Mass., assignor to
California Process Company, Los Angeles,
Calif., a corporation of Nevada

Application September 29, 1936, Serial No. 103,164

17 Claims. (Cl. 19—90)

This invention is a novel method of and means for opening, carding, and dusting or screening fibrous material such as wool and other animal fibres at one operation. In this case in accordance with official requirement I claim only the apparatus, but I propose to claim the method in a divisional application.

Foreign matters contained in matted or entangled fibrous material are difficult to separate and remove from the fibres, and to permit the removal of the foreign matters the contaminated fibrous material must be thoroughly opened up and the fibres separated.

The principal object of my invention is to enable the fibrous material to be thoroughly opened up and carded, and the dirt separated from the fibres at practically one operation by a novel apparatus by which such fibrous material is subjected to the alternate action of carding means and screening means in such manner that all portions of the fibrous material are repeatedly alternately carded and screened during a single passage of such material through the machine, and foreign matters are separated from the fibres during and simultaneously with the carding, or vice versa.

My apparatus includes preferably a rotary screening cylinder provided with internal pins for the purpose of lifting the fibrous material fed into the cylinder and dropping such material onto carding rolls or cylinders mounted within the cylinder, and preferably extending longitudinally of the axis thereof. The carding rolls catch the fibrous material and the fibres are carded in passing from one roll to another, and are removed from the last carding roll by a revolving brush; such operations being repeated upon the material as it progresses through the machine; and finally the cleaned and carded fibres are discharged.

In the accompanying drawings I have conventionally illustrated two embodiments of the invention, and will describe the same with reference thereto, but the invention is not restricted to the particular constructions shown, and I refer to the claims for summaries of the essential features of the invention and novel combinations and constructions of parts for which protection is desired.

50 In said drawings:

Fig. 1 is a side elevation of a machine embodying the invention, partly broken away.

Fig. 2 is a plan view thereof partly broken away.

55 Fig. 3 is a vertical section through the machine

on the line 3—3, Fig. 1, viewed from discharge end.

Fig. 4 is an end view of the machine showing the drive at discharge end.

Fig. 5 is a vertical section of a modified construction taken on the line 5—5, Fig. 6.

Fig. 6 is a vertical section through such machine on the line 6—6, Fig. 5.

Fig. 7 is a detail horizontal sectional view on the line 7—7, Fig. 5.

Referring to Figs. 1—4; a rotary screening cylinder 1 of any suitable construction may be mounted for rotation in a supporting framing 8, being shown as mounted on supporting rollers 1b attached to shafts 1c, journaled on the framing. 15 The cylinder may be kept in proper position upon the supporting rollers 1b by means of idler rollers 1g mounted on a shaft 1h which is journaled in spring tripped boxes 1i of any suitable construction.

20 The cylinder 1 can be rotated at any desired speed by any suitable means. Cylinder 1 may be from ten to twelve feet in length and about five or six feet in diameter; and is provided with internal pins 1a, which may be four or five inches 25 in length and spaced several inches apart. The pins may be arranged in rows, or in spiral lines if desired.

25 Within the cylinder are arranged a set of carding rolls 2, 3 and 4, which are provided with 30 carding cloth or teeth of any suitable kind. The carding roll 2 is arranged in about the horizontal plane of the axis of the screen, and is preferably set so as to clear the pins 1a on the interior of the screen. The carding roll 3 is arranged parallel with and above roll 2. The carding roll 4 is arranged parallel with and beside roll 2, and below roll 3. Roll 4 is preferably so located that its teeth intermesh with the teeth of both rolls 2 35 and 3 and will card the fibres therefrom.

35 Also mounted within the cylinder beside roll 4 is a rotating brush or cleaning roll 5, which may be provided with blades or wire bristles, adapted to remove fibres from roll 4 and throw them back into the cylinder.

40 The several carding rolls and brush roll may be journaled in bearings on the end members of the framing 8 in which the cylinder is mounted.

45 The diameter and length of the screening cylinder will depend somewhat upon the character 50 of the material to be treated and the amount of treatment required. The carding rolls may be of any suitable length and diameter, and any desired number of carding rolls may be employed. At present I preferably use three.

In the construction illustrated in Figs. 1 to 4, a plate 6 is arranged in the cylinder above the brush 5. Said plate is curved on an arc concentric to the axis of the cylinder, and extends from 5 a point opposite the outer side of brush 5, and somewhat below the axis of the cylinder, to a point adjacent the top of the cylinder and slightly beyond the vertical axis thereof. Plate 6 extends practically the full length of the cylinder and 10 may be supported on rods or bars 6b suitably mounted on the framing 8. The outer curved surface of plate 6 lies closely adjacent the path of movement of the inner ends of pins 1a. Preferably the upper end of the plate has a down- 15 wardly curved portion 6a which extends toward and closely adjacent to the inner side of carding roll 3.

When the machine (Figs. 1-4) is in operation, the cylinder is rotated in a clockwise direction 20 (as viewed from discharge end) (Fig. 3) and the fibrous material in the cylinder will be lifted by pins 1a and carried up to and moved over the plate 6 and dropped at the upper end thereof onto the portion 6a and be directed thereby onto 25 the carding roll 3.

The plate 6 may be provided with diagonal corrugations or vanes 6c on its upper surface and facing the interior of the cylinder, so that as 30 the material is moved upward over the plate by the pins it will also be shifted axially of the cylinder by such vanes; and thus at each revolution of the cylinder the fibrous material as it moves over the plate will progress longitudinally of the cylinder toward the discharge end thereof.

I preferably provide a shield 6e, Fig. 3, between 35 the lower outer end of the plate 6 and the lower end of the portion 6a, to confine the material more closely to the action of the brush and carding rolls.

The cylinder and rolls may be rotated at the 40 proper relative speed by any suitable means. One means is indicated in Fig. 4, and as there shown an electric motor M is mounted on the framing, and one of the shafts 1c carrying rollers 45 1b has a sprocket 1s driven by a chain 1t from a sprocket 1v on the shaft of the motor M. On the shaft of the motor is another sprocket 1a which leads to and over a tension take-up sprocket 1b, hung on spring hangers 1c; from 50 which it passes to and over a sprocket 4s on the adjacent end of the shaft of roll 4, and thence over a sprocket 5s on the adjacent end of the shaft of the brush roll 5, thence up over a sprocket 3s on the adjacent end of the roll 3, 55 thence down over a sprocket 2s on the adjacent end of the roll 2, and thence returns to sprocket 1a. By this arrangement the brush and each of the carding rolls can be driven at the desired relative speeds and in the desired direction. 60 While such drive is efficient I do not consider the invention restricted thereto.

The fibrous material to be treated can be fed 65 into one end of the screening cylinder 1 through a feed chute 9 and may be delivered at the other end of the cylinder into a discharge spout 9b having an inner end 9c adapted to receive the carded fibres swept off of the adjacent end of carding roll 4 by the rotating brush 5.

The screening cylinder 1 (Fig. 1) may be 70 revolved in a clockwise direction at a speed of approximately 5 to 50 R. P. M., depending upon the stock to be treated. Roll 2 revolved in a counter-clockwise direction. Roll 3 revolved in a clockwise direction at a slightly greater speed than roll 2. Roll 4 revolved in a counter-clockwise

direction at a higher speed than roll 3; and brush roll 5 revolved in a clockwise direction at a higher speed than roll 4.

As the screening cylinder 1 rotates the pins 1a 5 will raise portions of the fibrous material onto 10 plate 6 and move it thereover until the material drops from the plate onto the carding rolls. Most of the material would be deposited on rolls 3 and 2. The fibres caught by rolls 2 and 3 will be carded off by roll 4, which is moving at a 15 greater rate of speed; and the carded fibres are removed from roll 4 by the action of the more rapidly revolving brush 5, which throws the fibrous material onto the lower side of the screening cylinder. In such operation the fibrous material is opened up and the dust and foreign matters are loosened from the fibres and have an opportunity to separate from the fibrous material and pass through the screen. During its 20 passage axially of the screen cylinder the fibrous material is repeatedly subjected to the separating and carding action of the rolls; and the separated dirt passes out through the screen.

An advantage of the arrangement shown in 25 Figs. 1-4 is that the fibres are brushed from roll 4 in such manner that they do not pass under the carding rolls, so that any burrs or vegetable matter which drops out of the fibres while passing around the carding rolls will not drop back into the fibrous material but will drop 30 on a clean portion of the screen and have free opportunity of passing therethrough.

If desired the screen might be enclosed within 35 a housing such as 10 in the modification shown in Figs. 5 and 6; and also a short-fibre separating screen 16 might be used, as indicated in said figures.

In the modification shown in Figs. 5-7, the screen 1 is constructed and mounted as above described in a housing 10. The fibrous material 40 can be fed into one end of the cylinder through a feed chute 10a, and discharged from the other end of the screen into a spout 10b. The carding rolls 2, 3, 4, and brush 5, are arranged within the cylinder, as in Fig. 1, but the shield 6 is 45 omitted.

Roll 2 is set so as to just clear the pins 1a on the screen cylinder; roll 3 is set so that it will card the fibres from roll 2; and roll 4 set so that it will card the fibres from both rolls 2 and 3. 50 Brush 5 will remove the carded fibres from roll 4 as described.

In this modification the rotating screen 1 (see Fig. 5) may be revolved in a counter-clockwise direction (as viewed from discharge end) at a 55 speed of approximately 5 to 50 R. P. M., depending upon the stock to be treated; roll 2 revolved in a counter-clockwise direction at a speed sufficient to pick up and hold the stock raised by the pins 1a; roll 3 revolved in a clockwise direction 60 at a slightly greater speed than roll 2; roll 4 revolved in a counter-clockwise direction at a higher speed than roll 3; and brush roll 5 revolved at a higher speed than roll 4.

As the screen 1 (Fig. 5) rotates, pins 1a will 65 lift the fibrous material and part thereof will be taken by roll 2, from the pins as they pass such roll, and some of the material will be dropped from the pins (as they approach the vertical) onto the carding rolls; most of the material being 70 deposited on rolls 2 and 3. The fibres on rolls 2 and 3 will be carded off by roll 4; and the carded fibres are detached from roll 4 by the more rapidly revolving brush roll 5. And the clean carded fibres may be discharged from the 75

cylinder by chute 10b onto a conveyor 11 which delivers them to a suitable receiver, not shown.

The forward movement of the fibrous material in the cylinder may be obtained by tilting the entire screen and assembly of carding rolls, or by air currents, or by other suitable means provided for moving the stock forward.

In cases where the material to be treated contains considerable dust, it may be desirable to provide the housing 10 with an outlet 10c that can be connected with a suction fan (not shown) to withdraw any dust or light particles which pass through the screen.

If the fibrous material to be treated contains a large amount of short fibres and large particles of foreign matter, it may be desirable to provide the screening cylinder with larger openings or mesh. Such larger openings might permit the passage of an undesirable amount of short or broken fibres, and to recover such short fibres a flat shaking or vibrating screen 16 (Figs. 5 and 6) may be mounted under the rotating screen to collect the short fibres but permit the dirt to pass through. The short fibres can be discharged from screen 16 onto a conveyor 17 by which they may be carried to any desired point of deposit below the screen. The dirt passing through screen 16 will be caught on a bottom plate 16a and directed thereby into a suitable receiver.

30 The degree of opening and carding effect of the rolls is regulable as desired by varying the relative speeds and relative setting of the rolls. Some separation of the dust and foreign matter from the fibres will occur each time and at each point where one roll takes material from another, and where the fibres are thrown against the rotating screen.

The cylinder screen 1 may be of woven wire or of reticulated or perforated metal. The mesh of the wire or size of the perforations may be varied as desired along the length of the screen, depending upon the particular material to be treated. The screen surface of the cylinder may if desired be made in sections so mounted that they can be replaced, when worn, or replaced by screen sections of a different mesh or size or shape of openings.

The number of carding rolls, their size and location within the cylinder, their spacing with respect to one another, and the speed of rotation of each may be varied; as may best suit the particular material being treated. Also the shape of the pins, teeth, or clothing on the rolls 2, 3, 4, may be varied in spacing and character to suit the material to be treated. The spacing of such teeth may also be varied along the length of each roll as desired so that the carding action may be modified as the fibrous material advances along the length of the cylinder.

60 I claim:

1. Apparatus for opening, carding and cleaning fibrous material; comprising a rotatable screen, and fibre carding means in the screen including rotating elements with different peripheral speeds and adapted to repeatedly operate upon the fibres elevated by the screen.

2. Apparatus for opening, carding and cleaning fibrous material; comprising a rotatable screen, and fibre carding rolls within the screen rotating at different peripheral speeds and adapted to repeatedly operate upon the fibres in their passage along the cylinder.

3. Apparatus for opening, carding and cleaning fibrous material; comprising a rotatable screen, 75 fibre carding rolls within the screen rotating at

different peripheral speeds and adapted to operate upon the fibres in the screen, and means in the screen whereby the material is repeatedly delivered to the carding rolls for operation thereon, said carding rolls returning the material to the screen.

4. In apparatus for opening, carding and cleaning fibrous material; a rotatable screen, and a plurality of carding rolls extending longitudinally of and within the screen and rotating at different peripheral speeds operate upon the fibres within peripheral speeds adapted to repeatedly operate upon the fibres within the screen.

5. In apparatus for opening, carding and cleaning fibrous material; a rotatable screen, carding rolls rotating at different peripheral speeds and extending longitudinally of and within the screen and adapted to operate upon the fibres in the screen, and a rotary brush for removing the fibres from the carding rolls and throwing them 20 against the screen.

6. In apparatus for opening, carding and cleaning fibrous material; a rotatable screen, a plurality of carding rolls extending longitudinally of and within the screen and adapted to operate 25 upon the fibres in their passage along the screen, and a rotary brush for removing the fibres from the carding rolls and throwing them against the interior of the screen.

7. In apparatus for opening, carding and cleaning fibrous material; rotatable screening means, carding means extending longitudinally of and within the screening means adapted to operate upon the fibres, a plate for directing material to the carding means and means for lifting the 35 fibrous material onto and moving it over the plate to deliver it to the carding means.

8. In apparatus for opening, carding and cleaning fibrous material; rotatable screening means, carding means within and extending longitudinally of the screening means and adapted to operate upon the fibres; a plate for directing material to the carding means said plate being provided with means whereby the material is shifted longitudinally of the screening means as it is moved 45 over the plate, and means for lifting the material onto and moving it over the plate to deliver it to the carding means.

9. In apparatus for opening, carding and cleaning fibrous material; a rotatable cylinder, carding rolls within and extending longitudinally of the cylinder adapted to operate upon the fibres therein, a plate for directing material to the carding rolls, and means in the cylinder for lifting the material onto and moving it over the 55 plate to deliver it to the carding rolls.

10. In apparatus for opening, carding and cleaning fibrous material; a rotatable cylinder, carding rolls within and extending longitudinally of the cylinder adapted to operate upon the fibres therein, a plate for directing material to the carding rolls, said plate being provided with means whereby the material is shifted longitudinally of the cylinder as it is moved over the plate, and means in the cylinder for lifting 65 the material onto and moving it over the plate to deliver it to the carding rolls.

11. In apparatus for opening, carding and cleaning fibrous material; a rotatable screening cylinder, carding rolls extending longitudinally of and within the cylinder adapted to operate upon the fibres therein, a plate in the cylinder for directing material to the carding rolls, and means in the cylinder for lifting the material onto and moving it over the 75

plate to deliver it to the carding rolls, and means for removing fibres from the carding roll and returning them onto the screen.

12. In apparatus for opening, carding and cleaning fibrous material; a rotatable screening cylinder, carding rolls extending longitudinally of and within the cylinder adapted to operate upon the fibres therein, a plate in the cylinder for directing material to the carding rolls, said plate being provided with means whereby the material is shifted longitudinally of the cylinder as it is moved over the plate, means in the cylinder for lifting the material onto and moving it over the plate to deliver it to the carding rolls,
13. Apparatus for opening, carding and cleaning fibrous material; comprising a screen and fibre carding means within the screen including
- 20 rotating elements with different peripheral speeds and adapted to repeatedly operate upon the fibres, a housing enclosing the screen, and means for creating suction in the housing to remove light impurities separated from the
- 25 fibres.
14. In apparatus for opening, carding and cleaning fibrous material; a rotatable screen, a plurality of carding rolls rotating at different peripheral speeds and extending longitudinally of and within the screen and adapted to operate

upon the fibres within the screen, a housing enclosing the screen, and means for creating a suction in the housing to remove light impurities separated from the fibres.

15. Apparatus for opening, carding and cleaning fibrous material; comprising a rotatable screen, fibre carding rolls within the screen rotating at different peripheral speeds and adapted to operate upon the fibres in the screen, means in the screen whereby the material is repeatedly delivered to the carding rolls for operation thereon, the material being delivered from said carding rolls to the screen.

16. In apparatus for opening, carding and cleaning fibrous material; a rotatable screen, carding rolls rotating at different peripheral speeds extending longitudinally of and within the screen, means for removing fibres from the carding rolls and throwing them against the screen, and means whereby the material in the screen is repeatedly delivered to the carding rolls.

17. In apparatus of the character specified; a rotatable screen, a plurality of carding rolls extending longitudinally of and within the screen and adapted to operate upon the material in its passage through the screen, a brush for removing the fibres from the carding rolls and throwing them against the interior of the screen.

RUSSELL LEE BROWN. 30
